CONVERTIBLE PLAYPEN AND BED GUARD CONSTRUCTION

Alvin J. Randall, Evanston, Ill.

Application February 1, 1954, Serial No. 407,497

6 Claims. (Cl. 5—93)

This invention relates to children's playpens, and particularly it relates to children's playpens which are convertible into guard devices for beds.

Customarily, when a child reaches the age of approximately one and a half years, the parents are confronted with the problem of providing a suitable bed for the child other than a crib. Heretofore, at such time either a junior bed, which is substantially smaller than a conventional adult bed, or an adult bed, was provided for the child. Junior beds are provided with fixed rails and guard members to prevent the child from falling out. However, as conventionally manufactured, junior beds quickly become obsolete because the child outgrows the bed. In the latter instance, i. e. when an adult bed is provided, ample protection is not afforded an infant, too big for a crib, but too young for a bed not equipped with suitable guard means to preclude falling.

It is an object of this invention to provide a device that is originally used by a child until about the time it is ready to be removed from a crib and which thereafter becomes obsolete, as regards its original use, but which thereafter may be converted into a guard device for a standard bed.

Commercially available children's playpens, normally provide a plurality of rails defining a square, slightly in excess of 39 inches. Commercially available twin-size beds are substantially 39 inches wide.

It is an object of this invention to provide a playpen for a child which is adapted to be quickly and easily converted into a guard device for a conventional twin-size bed.

It is a further object of this invention to provide a child's playpen having an end member and a floor member connected to the end member, said end member and said floor member being removable from the playpen to thereby provide a guard device for a bed.

It is a still further object of this invention to provide a playpen which is convertible into a guard device for a bed, and which is adapted to be reconverted into a playpen.

Other and further objects of this invention will become apparent from the following description and appended claims, reference being had to the accompanying drawings and numbers of reference thereon.

On the drawings:

Fig. 1 is a perspective view of an embodiment of the invention, the removable end member and floor having been removed.

Fig. 2 is a perspective view of the removable end member and floor.

Fig. 3 is a vertical sectional view of the invention used as a bed guard and shown mounted about a standard twin-size bed.

Fig. 4 is a sectional view taken on the line 4—4 of Fig. 1.

Fig. 5 is a perspective view of an end portion of the support member.

2

Fig. 6 is a detail in perspective illustrating the female connecting element.

Fig. 7 is a detail in perspective illustrating the male connecting element.

Fig. 8 is a view illustrating the playpen in folded position.

Referring now more particularly to the drawings, the playpen, generally designated as 10, includes a pair of elongated vertical side members 11, 11, each of which comprises a pair of hinged sections 11a and 11b. Each of the side members 11, 11 includes a pair of hinged upper rails 12, 12 and a pair of hinged lower rails 13, 13, connected together by spaced vertical slats 14. A hinge 15 connects the rails 12, 12 of each of the side members 11, 11, as illustrated in Fig. 1; and a hinge 15a connects the rails 13, 13 of each of the side members 11, 11, thereby providing a means by which the rails may be folded inwardly, as illustrated in Fig. 8. To keep the side members 11, 11 rigid, a conventional pivoted latch 16 is mounted on each of the sections 11b and is releasably engaged on the lug 17, which is mounted on each of the sections 11a.

The head member 18 is hingedly connected to one end of each of the side members 11, 11 by means of a pair of suitable hinges 19, 19 mounted on the headboard 18, and on the respective vertical end rails 20, 20 of side members 11, 11.

The head member 18 may be either of a solid type fabrication as illustrated or an open type fabrication, similar to the construction of the side members 11, 11.

Casters 22, 22 are mounted in any conventional fashion on the bottom of the head member 18. A support member 23 is removably mounted on the head member 18, as illustrated in Figs. 1 and 4, by means of a plurality of releasable fasteners 24, only one of which is shown on the drawings. The fasteners 24, in the preferred embodiment, each comprises a screw having a large oval type head 26 that is extendable through a mating key-hole slot 27 in support member 23. The support member 23, in the preferred embodiment, comprises a metal tube of rectangular cross section that has a wooden plug 25 pressed into each end thereof, one being illustrated in Fig. 5. An angle pin 28 is secured in each wooden plug 25. By moving support member 23 upwardly from the position illustrated in Fig. 4, the support member 23 may be disengaged from head member 18.

One of the end supports 29, 29 is mounted on the end of each side member 11, 11. Each of the end supports 29, 29 has secured thereto, on the outer surface thereof, an upper female hinge plate 30 and a lower female hinge plate 31. A pair of casters 32, 32 are mounted in the conventional fashion on end supports 29, 29 respectively.

A removable end member 33, comprising an upper rail 34, a lower rail 35 and a plurality of spaced vertical slats 36, is removably securable to the side members 11, 11. The end member 33 has secured thereto, and integral therewith, on the opposite ends thereof, a pair of wide slats 37, 37 of a width sufficient to accommodate floor 38, when it is fully folded, as illustrated in Fig. 8. Each of the slats 37 has secured thereto an upper male hinge plate 39 and a lower male hinge plate 40, illustrated in detail in Fig. 7. Hinge plates 39 and 40 are each provided with a hinge pin 41 which is removably positionable in hinge barrels 42, 42 of respective female hinge plates 30 and 31.

The floor 38, previously identified, comprises section 43 and section 44, which are hingedly connected together by means of suitable hinges 45, only one of which is shown in Fig. 2. The free end 46 of section 43 rests upon the support member 23 when the device is used as a playpen. Further support is given floor 38 by angle brackets 21 secured to respective lower rails 13, 13, as

illustrated in Figs. 1 and 3. The floor 38 is secured to the lower rail 35 of removable end member 33 by suitable hinges, 48, 48.

To use the device as a guard means for a bed, the floor 38 is folded up against the slats 36 of removable end 33 and the latter is vertically lifted, thereby disengaging the pins 41 from the barrels 42. Thereafter, the support member 23 is disengaged from screw heads 26 and the connected side members 11, 11 and head member 18 are removed to the position illustrated in Fig. 3. The support member 23 is then positioned beneath bed 47, as illustrated in Fig. 3, the angle pins 28, 28 engaging the barrels 42, 42 of hinge plates 31, 31, as illustrated in phantom in Fig. 1, thereby providing a rigid bed guard.

Inasmuch as various changes may be made in the disclosed construction, and inasmuch as many widely differing embodiments may be constructed without departing from the spirit and scope of the invention, it is therefore intended that the specification and drawings not be interpreted in a limiting sense, but as illustrative only.

I claim:

1. A playpen comprising a pair of foldable side members, a head member hingedly secured to one end of each of said side members; an end member removably hinged to the other end of each of said side members; a transversely extending floor support member removably mounted on the head member; a floor hingedly secured to said end member, and a pair of connectors on said side members and opposite said head member, said connectors releasably mounting said support member when said end member is removed.

2. A device providing guard rails and a headboard for a bed, comprising a frame including three vertical members; a support member removably mounted on the ends of two of said vertical members opposite said headboard beneath the side rails of the bed and means on said headboard for releasably securing thereto said support member.

3. A playpen device having a removable floor and a removable end member and providing a guard and headboard for a bed, said guard and headboard comprising three vertical members of a playpen; a support member removably mounted on the outer ends of an opposed pair of said vertical members when said floor and end member are removed, said support being positionable on the other of said vertical members to thereby support the floor of the playpen only when all the playpen members are assembled.

4. A playpen device adaptable for use as a guard for a bed comprising a foldable floor; a vertical rigid end member pivotally secured to said floor; a pair of vertical foldable side members, said end member being removably and pivotally secured to said side members; a vertical head member pivotally secured to said side members; a floor support member removably secured to said head member and being normally mounted on the ends of said side members only when said end member is removed.

5. An article of manufacture being a convertible playpen and bed guard device and comprising a pair of opposed vertical playpen side members; a vertical playpen first end member being adapted to serve as a head board and being secured to said side members; connector means on the ends of said side members opposite said first end member; a vertical second end member releasably connected opposite said first end member to said side members; a playpen floor connected to said second end member and when in use extending inwardly toward said first end member, said second end member and said floor being removable from said playpen; a releasably mounted floor support mounted adjacent said first end member opposite the connector means when said article is used as a playpen, said floor support being connected to said connector means and disposed opposite said first end member when said second end member and floor are removed from the playpen to thereby provide a bed guard.

6. A convertible playpen and bed guard device comprising a pair of opposed vertical side members and a head member all being collapsably connected together; an end vertical member removably mounted on the outer ends of said vertical side members; a floor member secured to said end vertical member; a floor support releasably mounted adjacent the head member, the end portion of said floor member opposite said end vertical member extending inwardly toward said head member and bearing against said floor support when said device is used as a playpen, said floor support being releasably and operably connected to the outer ends of said vertical side members to hold them apart when said device is employed as a bed guard.
